UNITED STATES PATENT OFFICE.

WINFIELD HANCOCK YOST AND GEORGE BINET DOREY, OF MONTREAL, QUEBEC,
CANADA, ASSIGNEES TO RODGER BALLAST CAR COMPANY, OF CHICAGO, ILLINOIS,
A CORPORATION OF MAINE.

DEVICE FOR IMPARTING MOTION.

1,177,672.

Specification of Letters Patent.

Patented Apr. 4, 1916.

Application filed January 11, 1911. Serial No. 602,076.

To all whom it may concern:

Be it known that we, WINFIELD HANCOCK YOST, a citizen of the United States, and GEORGE BINET DOREY, a subject of the King 5 of Great Britain, both residents of the city of Montreal, in the Province of Quebec, Dominion of Canada, have invented certain new and useful Improvements in Devices for Imparting Motion; and we do hereby declare that the following is a full, clear, and 10 exact description of the same.

Our invention relates to operating mechanism of the type in which operation of a movable part is effected by an oscillatory or reciprocatory device adapted to alternately engage with and disengage therefrom; and further to manually operated devices of the 15 above type in which the manually operated member is adapted to remain out of operative relation with and adjacent to the said 20 part when the device is not in operation.

The invention has for its object to provide an improved device of this kind which will be more simple in construction and 25 easily operated than those heretofore known, and in which the parts will not be liable to get out of order when the device is in use.

Other objects and advantages of the invention will be apparent to those skilled in 30 the art from a consideration of the following description and accompanying drawings in which one form of construction embodying the invention has been described and illustrated and in which similar reference 35 characters indicate the same parts.

Referring now to the drawings: Figure 1 is a plan view of the device in use; Fig. 2 is a side elevation thereof; and Fig. 3 is an enlarged plan view of a portion of the device, the operating member being shown in 40 section.

In the embodiment of our invention herein illustrated the part to be moved comprises a vertical shaft *b* forming the brake mast of a car, a corner post and top plate of the car being shown at *c* and *d* respectively; this shaft having fixed thereon a device adapted to be engaged and moved by the operating mechanism, the device thus forming part of the shaft or other part to be moved or rotated. This device is preferably in the form of a ratchet wheel *e* keyed to the shaft as at *e'* and further secured thereto by a bolt *e''* passing therethrough and through the elongated hub of the ratchet 55 wheel and is adapted to be operated to rotate the shaft by a reciprocatory or oscillatory lever or handle *f* having a member preferably formed integrally therewith and through which it is adapted to automatically 60 engage and release the said device upon operation of the lever, this member as here shown being in the form of a pawl *g* adapted to engage the teeth of the ratchet wheel *e*.

The lever *f* with the pawl *g* is in the 65 present embodiment of our invention carried upon a bracket arm or carrier revoluble concentrically with the ratchet wheel, this carrier as here shown being formed by a two piece strap *h* loosely encircling an elongation of the hub *i* of the ratchet wheel and having upwardly extending ends *j*, a flange *l* on the hub *i* preventing longitudinal displacement of the carrier while the two parts of the strap are held in position by a hook 70 and slot connection *m* and a bolt *n* or other suitable means. The lever *f* is connected to the carrier to have a preferably limited movement relatively thereto in order that the pawl may be moved alternately in and 75 out of engagement with the ratchet wheel upon operation of the lever. We prefer to form this connection as follows: A bolt *h'* supported by the arms *j* of the carrier passes through a transverse opening in the 80 lever, such opening enlarging from the center toward the ends to form oppositely flared portions *o* and *o'* respectively, the sides of each of which are parallel to the opposite sides of the other as shown in Fig. 90 85 3, the lever having formed on opposite sides thereof, a pair of oppositely facing lugs *f''* adapted, as shown in Fig. 3, to bear against the ends of the carrier when the lever is in engagement with the ratchet wheel in order 95 to prevent undue strain on the bolt *h'*. By means of this connection the lever *f* has limited movement relatively to the carrier, the limiting of this movement being effected by the parallel sides of the opening engaging 100 the bolt *h* and the lugs *f''* bearing upon the ends *j* of the carrier. It will thus be seen that the lever and carrier together form a jointed lever the relative movement of the parts of which causes the lever to engage 105 with and disengage from the ratchet wheel upon operation thereof.

The above described connection also forms

a gimbal joint between the lever and carrier, which form the relatively movable parts of the jointed lever, and allows the lever *f* to swing in different planes to permit of its dropping or being moved to the position shown in dotted lines in Fig. 2 in which position it will be out of the way of, and not liable to strike against or be struck by passing or adjacent objects, and in which position the pawl is completely removed 10 from operative relation with the ratchet wheel. It will be also noted that this construction provides a direct connection between the lever and carrier permitting of movement of the lever in planes at right 15 angles to each other. The upper side of the engaging end of the pawl *c* is preferably provided with a forwardly extending flange *g* adapted to bear against the top of the ratchet wheel and limit the upward swing 20 of the handle past its proper operative position which is shown particularly in Fig. 2.

The shaft may be located against reverse rotation by any suitable means as the 25 weighted pawl *p* mounted on a bracket *r* bolted to the corner post *c*, this pawl engaging a second ratchet wheel *s*, fixed upon the shaft *b*, and being held yieldingly in engagement with the ratchet wheel by a weight *t* pivoted on the bracket *r* and normally resting on the tail *r'* of the pawl.

When the device is not in use the operating handle *f* hangs in the position shown in dotted lines in Fig. 2. When it is desired to 30 rotate the shaft this handle or lever is swung to the position shown in full lines in Fig. 2, in which position the pawl is in operative relation with the ratchet wheel with which it is then engaged by a slight forward horizontal movement of the handle, the further 35 movement of the handle in the same direction causing the ratchet wheel and with it the shaft to be rotated as will be readily understood, while upon the reverse movement of the handle the pawl will be withdrawn from engagement with the ratchet wheel, and the lever and the revoluble bracket will swing backward together, the pawl *g* automatically reengaging the ratchet 40 wheel when the lever is again moved forward. When the operating handle is released it will fall by its own weight to the 45 position shown in dotted lines in Fig. 2 with the pawl removed from operative relation 50 with the ratchet wheel.

What we claim is as follows:

1. The combination with a part to be moved, of operating means including a bodily movable carrier and a lever fulcrumed upon the said carrier to move relatively thereto parallel to the plane of movement thereof, and adapted to engage the said part, and move said carrier and part in unison, and means carried by the said 60 carrier and lever for limiting the said relation

tive movement thereof upon movement of the lever into engagement with the part to be moved.

2. The combination with a part to be moved, of operating means including a 70 jointed reciprocatory lever, the parts whereof have relative movement in the plane of operative reciprocation of the lever whereby the lever is caused to engage with or disengage from the part to be operated, and 75 means independent of the part to be moved for limiting the said relative movement of the lever parts in both directions.

3. The combination with a part to be moved, of operating means including a 80 jointed reciprocatory lever, the parts whereof have relative movement in the plane of operative reciprocation of the lever whereby the lever is caused to engage with or disengage from the part to be operated, and 85 means independent of the part to be moved for limiting the said relative movement of the lever parts upon being moved to a position to cause the lever to engage the said part to be moved, for the purpose set forth. 90

4. The combination with a part to be rotated, of an arm pivoted at one end concentrically to such part, a lever adapted to engage and rotate such part and means providing a gimbal-joint connection between the lever and the other end of said arm whereby the lever may be swung in one direction relatively to said arm and also in another direction relatively to such arm and at right angles to the first direction. 100

5. The combination with a part to be moved, of an arm pivoted at one end concentrically to such part and a lever adapted to engage and rotate such part, the lever being pivoted to the opposite end of the arm 105 and having two swinging movements independently of the latter and in two distinct directions with relation to such arm.

6. The combination with a part to be moved, of an arm pivoted at one end concentrically to such part, a lever adapted to rotate said part and presenting a flared opening and a pivot pin carried by the arm and located in said flared opening. 110

7. The combination with a shaft, of a carrier and a lever supported by said carrier, such lever having a swinging movement transversely of the shaft and independently of the carrier and a swinging movement in the longitudinal line of the shaft and independently of the carrier. 120

8. The combination with a shaft, of a carrier and a lever supported by said carrier, such lever having a horizontal swinging movement independently of the carrier 125 and a vertical swinging movement independently of the carrier.

9. The combination with a part to be moved, of operating means, including a jointed lever, one of the parts whereof is 130

formed with a transverse opening enlarging from the center toward the ends, and means connecting such parts together through the said opening.

5 10. The combination with a part to be moved, of operating means, including a jointed lever, one of the parts whereof is formed with a transverse opening enlarging from the center toward the ends to form 10 oppositely flared portions the sides of each of which are parallel to the opposite sides of the other, and means connecting such parts together, including a member carried by the other part and passing through the 15 said opening.

11. The combination with a rotatable part, of an arm pivoted concentrically thereto at one end and a reciprocating lever connected to the other end of the arm by a gimbal-joint connection whereby the lever may be swung in one direction relatively to said arm and also in another direction relatively to such arm and at right angles to the first direction, such lever having a member thereon adapted, when the lever is swung, to engage and rotate said rotatable part, the member having a flange extension adapted to bear against said part to be rotated and limit the movement of the lever with respect thereto in a direction vertical to its plane of operative reciprocation.

12. The combination with a part to be moved, of operating means, including a jointed lever one of the parts whereof is

formed with a transverse opening enlarging 35 from the center toward the ends, and means connecting such parts together, including a bolt carried by the other part and extending through the said opening.

13. The combination with a part to be moved, of operating means including a jointed lever one of the parts whereof is formed with a transverse opening, and means connecting the said parts together, including a bolt passing through the said 40 opening in a direction common to the plane of operative movement of the lever and carried by the other part, the ends of the opening being of substantially greater dimensions than the adjacent parts of the bolt. 45

14. The combination with a part to be moved, of operating means comprising a jointed lever, the parts whereof have relative movement in the plane of operation of the lever, and means for limiting such 50 movement in one direction including a pair of lugs formed on one lever part on diametrically opposite sides of the point of connection of the lever parts and adapted to bear against the other lever part. 55

In testimony whereof, we have signed our names to this specification, in the presence of two subscribing witnesses.
